(57) **CLAIM**

(52) **U.S. Cl.**

We claim the ornamental design for a computer, as shown and described.

USPC **D14/314**; D14/371

DESCRIPTION

(58) **Field of Classification Search**

FIG. 1 is a perspective view of the claimed design;

USPC D14/371-376, 125-129, 336, 337, 447,

FIG. 2 is a front elevational view thereof;

D14/448, 451; D6/300, 308, 329, 641,

FIG. 3 is a rear elevational view thereof;

D6/642, 682, 708, 708.17; D19/113, 114;

FIG. 4 is a right side elevational view thereof;

D20/10

FIG. 5 is a left side elevational view thereof;

CPC G09F 15/0025; G09F 15/0062; G09F

FIG. 6 is a top plan view thereof; and,

15/0068; G06F 1/16; G06F 1/1613; G06F

FIG. 7 is a bottom plan view thereof.

1/133308; G06F 1/1601; G06F 3/037;

The broken lines shown in the drawings form no part of the

G06F 1/162; F16M 11/02; F16M 11/10;

claimed design. Further, the broken away lines in the draw-

F16M 11/00; F16M 11/06; F16M 11/14;

ings indicate an indeterminate length, and the portion of the

F16M 11/18; F16M 11/045; F16M

(Continued)

11/105; F16M 11/041; F16M 11/126;

F16M 11/04; F16M 11/24; F16M 13/02;

computer that may be visible between the broken away lines
forms no part of the claimed design.
